FOOT COVERING

Theotiste N. Herbert, Merion, Pa.

Application November 4, 1944, Serial No. 561,871

2 Claims. (Cl. 66—187)

2

This invention relates generally to knitted foot coverings and more particularly to a knitting article which is adapted to be worn over the toe portion of the foot either as a protector for the conventional hosiery as normally worn or as a protective device for medication, such as salve, powder or liquid, which is applied to the skin of the foot in the treatment of various skin diseases.

Among the principal objects of the present invention is to provide a simple and inexpensive foot protector which is adapted to be fitted snugly and comfortably over the toe portion of the foot and which is of such construction that it may be worn inside of the conventional sock or stocking without any discomfort whatsoever to the wearer.

Indeed, a further and important object of the present invention is to provide a toe protector of the above character which is of such seamless or circular knit construction that it is devoid of any longitudinally extending seams, in consequence of which the present protector, when worn inside the foot of a sock or stocking having the usual seam in the bottom thereof, cushions the ball of the foot against the discomfort occasioned by the seam normally present in the foot of the sock or stocking.

Still another object of the present invention is to provide a toe protector, the bottom or sole portion of which is knitted to provide the same with a soft, absorbent cushion and the free or open end of which is knitted to provide it with a cuff of such circumferential elasticity as to insure snug and comfortable retention of the protector about the toe portion of the foot.

Other objects and advantages of the present invention will appear more fully hereinafter, it being understood that the present invention consists substantially in the combination, construction, location and relative arrangement of parts, all as described in detail hereinafter, as shown in the accompanying drawing and as finally pointed out in the appended claims. In the said accompanying drawing, which illustrates a preferred embodiment of a toe protector constructed in accordance with the principles of the present invention—

Figure 1 is a view showing the toe covering in place upon the foot of a wearer;

Figure 2 is a top plan view of the covering;

Figure 3 is a side elevational view thereof when the same is folded with its opposite sides in flat-wise engagement with each other; and

Figure 4 is a sectional view taken on the line 4—4 of Figure 3.

Referring now to the drawing, it will be observed that the protector of the present invention is preferably formed of a seamless or circular knit main body part 10 which is adapted to be snugly fitted over the toe portion of the foot, the front or toe end 11 of the body being closed while the rear end thereof, which is open as at 12, terminates in a cuff or welt 13. As is well understood in the art, by so forming the protector body of a seamless or circular knit construction, it is rendered free of any longitudinally extending seams therein, the absence of which, particularly in the bottom or sole portion of the protector, provides for greater comfort to the wearer whose feet might be sensitive to such seams. However, where such a seam may not be objectionable, the protector of the present invention may well be formed of a flat knit, full-fashioned fabric, the opposite edges of which are seamed together in accordance with conventional practice in the manufacture of full-fashioned knitted hosiery.

In the present instance, as illustrated in the accompanying drawing, the seamless or circular knit body of the protector 10 is initially produced in the form of a tubular fabric upon a circular knitting machine, the cuff or welt 13 being topped on to the needles of the machine which then continues to knit the upper foot portion 14 and the lower foot-sole portion 15 down to the inner end or point 16 of the toe gore 11. Thereafter, by reciprocatory knitting, the toe pocket 18 is produced, this pocket being composed of the upper and lower toe portions 19 and 20. The protector body is then completed by looping the forward end of the upper foot portion 14 to the rear edge of the upper toe portion 19, along the line 21.

In order to provide the foot protector of the present invention with a cushioned sole portion, an additional yarn 22 is preferably interknitted with the main body yarn 23 to form elongated terry loops 24 on the inside face of the lower foot-sole portion 15 of the protector (see Figure 4). Preferably, the yarn forming these terry loops is introduced to the needles of the knitting machine in such relation to the body yarn as to carry the terry loop yarn to the back of the knitted fabric, that is, to that face of the fabric which is to form the inside of the protector, thereby rendering the terry loops invisible from the outside of the knitted article. The desired elongation of the terry loops may be obtained in

any suitable manner to provide the necessary cushioning surface on the inside of the bottom or sole portion of the protector, and if desired, the elongated terry loops may be brushed to produce a fleece effect over the entire extent of said bottom or sole portion of the protector.

The cuff or welt 13 of the protector, formed in each instance with a selvaged or otherwise finished edge 25, is preferably formed of circular knit fabric in which is incorporated an elastic yarn or thread in accordance with conventional practice well known and understood in the art, such elastic yarn being preferably incorporated in a plurality of spaced, circular courses of the knitted cuff or welt to provide the same with a greater degree of elasticity than is characteristic of the main body of the protector.

It will be noted that the main body portion of the toe protector is knitted of such shape and elasticity as to snugly and comfortably fit about that portion of the foot which extends forwardly of the instep and that the length of the protector is extended by the cuff or welt 13 only sufficiently to encompass the forward portion of the instep. The cuff or welt 13 with its interknitted elastic yarn is provided with an inherent elasticity greater than that of the main body portion of the protector, to thereby enable said welt to snugly and comfortably conform to the shape of the foot in the immediate region of the arched instep portion thereof and so retain the protector in position upon the foot.

It will be understood, of course, that this invention is susceptible of various changes and modifications which may be made from time to time without departing from the real spirit or general principles thereof, and it is accordingly

intended to claim the same broadly as well as specifically as indicated by the appended claims.

What is claimed as new and useful is:

1. A covering adapted to be slipped over the toe and front sole portion of the foot having a main body part of plain knit fabric shaped to conform to said portion of the foot and having a toe pocket at its frontal end and a cuff or welt at its rear end adapted to snugly fit about the foot in the immediate region of the arched instep portion thereof, said toe pocket being provided in its opposite sides with longitudinally extending gore lines each extending from the rear end of the pocket to a point short of its front end with the upper and lower rear edges of said pocket respectively defined by lines disposed in angularly related transverse planes intersecting one another at the rear terminal points of said gore lines, and said cuff or welt being so knitted that when unextended it is of a circumferential length substantially less than the unextended circumferential length of the said main body part of the covering and having such stretch characteristic relatively to that of said main body part as to permit it (said cuff or welt) to be circumferentially extended to a degree greater than is possible in any portion of said main body part of the covering.

2. In a foot covering of the character defined in claim 1 wherein the main body part thereof throughout the region extending between the lower rear edge of the toe pocket and the terminal cuff or welt is interknitted with a yarn formed into terry loops to provide a cushioned surface on the inside face of the sole portion of the covering.
